UNITED STATES PATENT OFFICE.

MICHAEL H. LANTZ, OF MARIONVILLE, MISSOURI.

RAILROAD-GATE.

SPECIFICATION forming part of Letters Patent No. 286,718, dated October 16, 1883.

Application filed December 6, 1882. (No model.)

To all whom it may concern:

Be it known that I, MICHAEL H. LANTZ, a citizen of the United States, residing at Marionville, in the county of Lawrence and State 5 of Missouri, have invented a new and useful Railroad-Gate, of which the following is a specification, reference being had to the accompanying drawings.

This invention relates to railroad-gates, and 10 has for its object to provide a simple, durable, inexpensive, and efficient gate that will be automatically operated by the train, will have no spring mechanism liable to become worn or inoperative, and will be stock-proof.

15 In the drawings, Figure 1 is a perspective view of a portion of a railroad-track having my improved gate and its governing mechanism. Fig. 2 is a side view thereof. Fig. 3 is a transverse vertical sectional view taken 20 through the gate. Fig. 4 is a top view of the track and gate mechanism.

Referring to the drawings, A, A designate the rails of the track, which are secured by cross-ties in the usual manner. B is the 25 gate, which is arranged transversely in relation to the track, and has a base-shaft, C, that is journaled in suitable boxes, D, depending from the rails, and carrying friction-rollers E, as shown. At one end of the rock-shaft C is 30 arranged a returning weight, F, and from the said shaft project the pickets G, that comprise the body of the gate. These pickets may consist each of but one metallic rod projecting singly from the shaft; or the rod may, for purpose 35 of greater strength, be bent double and have the ends thus formed enter the shaft on diametrically opposite sides and relatively disposed diagonally, all as shown at H. Near the weighted end of the shaft is fixed a plate, I, having a segmental bottom edge, J, and a shoulder, K, at each side above this edge. Each of these side shoulders are adapted to 40 engage the crank and weighted end L (the weights being denoted by the letter M) of a transverse shaft, N, that has bearings in boxes 45 O, depending from the rails. On the side of the track opposite their weighted ends these shafts N N have extensions P at right angles to their main portions, and said extensions 50 carry a false track or plate, Q, that is parallel

with the adjoining rail, and normally projects above the latter. This plate Q is also provided with any desired number of additional bearing-rod R, comprising, like the lock-rod N N, an extension, S, and main portion or 55 body T at right angles to the latter, and journaled in boxes U, depending from the rails. The false track Q is adapted to be depressed by the tread of the wheels to the horizontal plane of the track in either direction. When 60 it is thus depressed, its shaft N on the side of the gate from which the train approached is thrown over, so that its weighted crank end is thrown out of engagement with the shoulder K of the segmental plate I, while the cranked 65 and weighted end of the other rock-shaft N is thrown farther over into more positive engagement with the shoulder of the plate I. The gate is thus unlocked, so that it can be thrown down from the side of the approaching 70 train, but is still locked in vertical position against any pressure, by stock or otherwise, from the side opposite to that from which the train is approaching. When the train reaches the gate, the pilot of the locomotive 75 strikes a centrally-disposed re-enforcing plate, V, secured by the pickets, and the gate is thereby readily thrown down to admit of the passage of the train. The ends of the false track or plate Q are provided with lateral 80 right-angular extensions W, which form plates X parallel with the plate Q. To the top of each of these plates X is hinged another plate, Y, extending down between the plates X and Q, and having beveled under edge, Z. From these 85 hinged plates Y extends an angular bracket-rod, A'. The object of this hinged plate mechanism is to hold the gate down while the train is passing. Under ordinary circumstances it is not necessary that the gate be secured down; 90 but at places where trains are switched back and forth slowly this mechanism is desirable.

The just-described latch mechanism operates to hold the gate down as follows: As the gate is thrown down by the pilot of the locomotive, the picket adjoining the outer side of the plate Q, which picket is in this instance provided with a lateral top extension, B', passes between the plates Y and Q until its lateral head-extension B' clears the hinged 95

plate Y, when the end picket of the gate strikes the rod A', so that the latter throws the hinged plate Y out from the plate X and over the extension B'. After the train has passed, the 5 plate Q resumes its normal position, through the operation of the weights M, which disengages the extension B' and allows the gate to also resume its normal position. When the train approaches slowly the force may not always be sufficient to throw the gate down far enough to engage the latch mechanism; but to insure engagement under these circumstances I provide the gate with a picket having a diamond-shaped or enlarged head, C', that will 10 project above the rail and be depressed by the tread of the wheels to lower the gate the necessary distance.

It will be observed that all the weights are pivotally hung on their respective rock-shafts, 20 which relieves the latter from strain and admits of ready operation of the weights to return the mechanism to its normal position.

It will also be observed that all the mechanism is connected to the rails, so that it can 25 be removed, applied, or changed in position without interfering with the ties or necessitating tearing up of the track.

Ordinarily the weights can hang at the side of the embankment or in the ditch at the side 30 of the track; but on level ground I prefer to turn the ends or cranks of the rock-shafts up, so that the weights and locking mechanism will be above the surface of the ground.

I claim as my invention—

35 1. A railroad-gate having a base rock-shaft provided at one end with a returning-weight, and a locking-plate that is engaged by locking rock-shafts to retain the gate in a vertical position, the gate being arranged transversely in 40 relation to the track, and adapted to be unlocked by the approaching train and thrown down to admit of passage of the latter, as set forth.

45 2. A railroad-gate having a base rock-shaft provided with a returning-weight at one end, and a vertically-disposed locking-plate having a segmental under edge, above which are formed side shoulders, in combination with

two weighted rock-shafts engaging these shoulders, and which are thrown out of engagement 50 with the same by the approaching train, as set forth.

3. In combination with a railroad-gate journaled transversely in relation to the track, a false track or plate parallel with the track, and adapted to be depressed to the horizontal plane thereof by the tread of the wheels, said plate being provided with latch mechanism for holding the gate down, which automatically releases the gate after passage of the train, as set forth. 60

4. The combination of a railroad-gate having a base rock-shaft journaled transversely in relation to the track, a plate arranged parallel with the rail and pivoted thereto, so as to be normally on a higher horizontal plane, 65 but adapted to be depressed to the plane of the track by the tread of the wheels, and latch mechanism, consisting of a hinged plate arranged on the pivoted plate and adapted to automatically engage and release one of the 70 pickets of the gates, as set forth.

5. The combination of the gate having a transversely-journal rock-shaft, provided with a returning-weight, and locking-plate having side shoulders, the tread-plate arranged 75 parallel with the rail and adapted to be depressed by the tread of the wheels, and the transverse rock-shafts carrying the said plate and provided with weighted ends that engage the shoulders of the fixed locking-plate, as set 80 forth.

6. A railroad-gate transversely disposed, and adapted to be thrown down by the pilot of the locomotive and held down by suitable latch mechanism; provided with a picket having an enlarged head that will project above the adjoining rail and be depressed by the tread of the wheels, as set forth. 85

In testimony that I claim the foregoing as my own I have hereto affixed my signature in 90 presence of two witnesses.

MICHAEL H. LANTZ.
